UNITED STATES PATENT OFFICE.

WILLIAM J. RANDOLPH, OF OBERLIN, LOUISIANA.

THRASHING-MACHINE.

SPECIFICATION forming part of Letters Patent No. 555,533, dated March 3, 1896.

Application filed August 2, 1894. Serial No. 519,287. (No model.)

To all whom it may concern:

Be it known that I, WILLIAM J. RANDOLPH, a citizen of the United States, residing at Oberlin, in the parish of Calcasieu and State of Louisiana, have invented a new and useful Thrashing-Machine, of which the following is a specification.

This invention relates to thrashing-machines; and it has for its object to provide certain improvements in thrashing-machines whereby shaking and vibrating separating devices and carriers are dispensed with, while at the same time providing means for a more effective separation of the grain being operated upon.

To this end the main and primary object of the present invention is to provide an effective thrasher having no vibrating or shaking parts to become displaced and out of order.

With these and other objects in view, which will readily appear as the nature of the invention is better understood, the same consists in the novel construction, combination and arrangement of parts hereinafter more fully described, illustrated, and claimed.

In the accompanying drawings, Figure 1 is a central longitudinal sectional view of a thrashing-machine constructed in accordance with this invention. Fig. 2 is a detail sectional view on the line $x-x$ of Fig. 1. Fig. 3 is a detail in perspective of one of the swinging screen-plates of the adjustable riddle. Fig. 4 is a detail in perspective of a section of one of the endless riddle-chains having the pivot-pins. Fig. 5 is an enlarged detail sectional view of one of the swinging screen-plates. Fig. 6 is an enlarged detail sectional view of the upper end of the endless riddle. Fig. 7 is a detail transverse sectional view 40 showing the attachment of the inclined guard-boards at the sides of the riddle-frame, shown in Fig. 1 in dotted lines. Figs. 8 and 9 are side elevations of the machine, showing the gearing for speeding the straw-carriers, the beaters, and the grain-wheels.

Referring to the accompanying drawings, A represents the casing of my improved thrashing-machine, which is constructed in the usual shape and is of a size according to the work required of it. The machine-casing A is mounted on the ordinary truck-wheels a , which provide for the ready transportation of

the machine from place to place, and at the feeding end thereof is arranged the usual feed board or table B, onto which the grain 55 is placed and fed to the thrashing-cylinder C. The thrashing-cylinder C is of the ordinary construction provided with the cylinder-teeth c , and working over the cylinder-concave c' , arranged directly thereunder at the inner end 60 of the feed board or table. In the present invention the usual grate arranged beyond the inner end of the cylinder-concave is dispensed with in order that the straw, after leaving the concave, may be thrown directly onto the first 65 inclined slatted straw-carrier D, while the grain thrashed out of the straw by the cylinder falls through the concave c onto the cylinder cant-board d, which directs such grain onto the main grain-board E, up which the 70 grain is carried by the endless grain-carrier F, the upper portion of which works on top of the said grain-board.

The first straw-carrier D, is arranged directly over the grain-carrier F and beyond 75 the cylinder and its concave, so as to not only receive the straw and grain from the cylinder, but also to provide for allowing the separated grain, loosened from the straw while 80 on the straw-carrier, to also fall onto the main grain-board E, and be elevated thereon by the carrier F.

The straw-carrier D is of a simple slatted construction, comprising the opposite endless chains or belts e, passing over the upper 85 and lower sets of chain-wheels e' , suitably connected by the closely-arranged transverse triangularly-shaped or pointed slats e^2 , thus providing a construction which readily elevates the straw, while permitting the loosened grain 90 to fall directly therethrough and between the upper and lower portions of the slatted carrier D onto the carrier F, therebelow. The upper portions of the endless chains or belts e are adapted to pass over the longitudinally 95 disposed supporting cleats or strips e^3 , arranged under the upper portion of the carrier D and between the upper and lower chain or belt wheels e' , for the purpose of preventing downward sagging of the said carrier D.

The first straw-carrier D is arranged at an inclination within the casing A in order to provide for the proper separation of the grain from the straw while being carried thereby,

- and such carrier has imparted thereto a comparatively rapid motion of about two hundred feet per minute, while directly thereabove, at about a distance of four inches and in as close proximity to the cylinder C as possible, is mounted a rapidly-revolving beater G. The beater G is provided with a radial series of wings g, which serve to strike down the straw as it leaves the machine-cylinder and beat the same onto the carrier D. The rim of the winged beater G is adapted to travel in the direction indicated by the arrow, about three or four times as fast as the carrier D, and combines with such carrier to knock and tear the straw, whether wet or dry, so as to effect a thorough separation of the grain therefrom, such thrashed grain falling through the carrier D onto the grain-carrier F, as previously described.
- 20 The grain-carrier F is constructed in a substantially similar manner to the slatted straw-carrier D and comprises the opposite endless chains f, passing over the upper and lower sets of chain-wheels f' and connected by the transverse slats f², which slats are preferably attached to lugs on the links of the chains f and serve to elevate the grain on the grain-board E.

The slatted grain-carrier F is arranged at an inclination within the machine-casing A and extends from the front end to an intermediate point beginning at a point below and beyond the lower end of the cant-board d and ending at its upper end at a central or intermediate point within the casing, and the main grain-board E, which is arranged under the upper portion of the carrier F, extends from end to end of such carrier, beyond the rear upper end of which is formed a grain-space H, through which the grain falls after being elevated up and over the outer end of the grain-board.

Beyond the upper end of the first straw-carrier, D, and the upper end of the main grain-board E and over the grain-space H is arranged a second slatted straw-carrier, D'.

The straw-carrier D' is constructed similar to the carrier D; but to the second straw-carrier is imparted a faster motion than to the carrier D, the carrier D' being given a motion of about two hundred and twenty-five feet per minute. At a point directly between the upper discharging end of the carrier D and the lower receiving end of the carrier D' is arranged an intermediate winged beater I, which is given a rotation in a direction which causes it to carry the straw received from the carrier D on the top portion thereof, and to throw it toward a faster-rotating beater I', which is arranged directly over the carrier D' and slightly closer thereto than the beater G is to the carrier D. The beater I' rotates much faster than the beater I and in a direction opposite to the rotation of the latter beater, so that the straw is buffeted between the said beaters in order that any grain which may be clinging thereto will be thrashed out

of the same, and be caused to pass through the slats of the carrier D' into the grain-space H.

The thrashed straw is elevated by the second straw-carrier, D' onto a beater i arranged in the same position beyond its upper end as the disposition of the beater I beyond the carrier D, and said beater i is adapted to rotate in combination with an adjacent reversely and more rapidly rotating beater i', and these two beaters agitate the straw directly over a third inclined slatted straw-carrier, D².

The inclined slatted straw-carrier D² is of identically the same construction as the first carrier, D, and need not be further described; but it is to be noted that this carrier is given a faster speed than either of the other two preceding carriers and is made to travel at about the rate of two hundred and fifty or two hundred and seventy-five feet per minute, and in order to positively insure the separation of any remaining grain in the straw at this point of the thrasher the beater i' is disposed nearer to the top face of the carrier D² than either of the corresponding beaters preceding.

In connection with the beaters that are arranged over each of the inclined carriers it is to be noted that the longitudinal supporting strips or cleats, such as described in connection with the first carrier, D, will prevent the carriers from jumping or sagging away from the beaters, so as to make the action of the beaters positive.

The third inclined straw-carrier, D², is arranged at the rear end of the thrashing-machine and delivers the straw into the rear straw-chute J, that is extended any distance from the rear end of the machine-casing to provide for delivering the straw onto the stack, and immediately under and extending longitudinally of the said straw-carrier D² is arranged an inclined grain-board j, that catches the thrashed grain which falls through the said slatted carrier and directs such grain back toward the center of the machine and into the grain-space H, through which substantially all of the thrashed grain passes, for the purpose to be presently described.

The number of the straw-carriers may be varied, and in the event of constructing a machine with a greater number of these straw-carriers arranged successively the speed of such carriers would differentiate successively in a similar manner to the differentiation of the speed of the carriers D, D' and D², already described, and it is therefore to be observed that there is not only differential speeds between the beaters and the straw-carriers and the straw-carriers themselves, but also between beater and beater, so that means are provided for giving the straw violent agitation without any danger of throwing the grain out of the machine, and also making it impossible for the thrashed grain to ride out of the machine in the straw.

All the grain thrashed from the straw is mainly directed to fall through the grain-space H onto the endless riddle L, which is arranged at an angle within one end of the 5 machine-casing A directly under the upper portion of the grain-carrier F. The endless riddle L is mounted on and is adapted to travel over a riddle-frame M. The riddle-frame M comprises the opposite braced side 10 bars m, which are connected and braced together by means of suitable frame-bars and brace-rods m', and to the inner extremities of the side bars m are attached the offstanding bearing-arms N, which project beyond the 15 ends of the bars m and form bearing-supports for the opposite wheel-shafts n. The opposite wheel-shafts n carry thereon, at one side of the bearing-arms N, the sprocket or chain wheels O, which are thus disposed in a 20 line with and beyond the ends of the side bars m, and the upper one of said wheel-shafts n is extended beyond the wheels O carried thereby and projects through the opposite sides of the machine-casing A, so as to 25 form a pivotal support for that end of the riddle-frame.

At an intermediate point the opposite side bars m of the riddle-frame M have secured thereto the offstanding bolt-arms P, which 30 project through and work in the curved slots p formed in opposite sides of the machine-casing A and are engaged at their outer ends by the binding-nuts p', which, together with such bolt-arms, provide means for adjusting 35 the angle of the slant of riddle-frame to adapt the same to the different kinds of grain being operated upon.

The sprocket or chain wheels O, arranged 40 in pairs at opposite ends of the riddle-frame M, are adapted to receive the opposite parallel chains Q, every other link of which chains is provided with an inwardly-extending pivot-pin q adapted to loosely receive the opposite angled ends of the transverse plate-bars R. 45 The transverse plate-bars R are provided with opposite angled perforated ends r to loosely engage the pivot-pins of the chains Q and have attached thereto the flanged ends r' of the perforated screen-plates S.

50 The perforated screen-plates S extend from side to side of the riddle-frame and have the opposite ends thereof slightly overlap the chains Q to prevent the grain from working off through said chains, and such plates are 55 of a width so that their free edges will overlap the pivoted edge of the adjacent plate when forming the upper portion of the travelling riddle L; but by reason of the pivotal connection of such plates with the opposite 60 chains Q the same, of their own weight, will assume a vertical position when forming the under portion of the riddle, as clearly illustrated in Fig. 1 of the drawings, in order to leave unobstructed passages for the grain to 65 fall through after working its way through the overlapped plates on the upper portion of the riddle.

The swinging or pivoted screen-plates S are preferably provided with elongated separating openings or perforations s, which are more 70 effective in the separation of oats and similar grains, and to the under side of the several screen-plates are preferably attached the adjustable slide-plates T. The slide-plates T are provided with a series of openings or perforations t, corresponding to those in the screen-plates, and such slide-plates are adjustably clamped to the screen-plates by the bolts t', whereby the size of the openings or perforations in such screen-plates may be varied to 80 suit the grain being operated upon.

Arranged above the lower end of the endless riddle L, and suitably attached to the frame M thereof, is a stop-board U, disposed transversely of the casing A, and such stop-board prevents the grain from working off at the lower end of the riddle, while the grain is prevented from working off at the side of the riddle and is held thereon by means of the opposite side guard-boards u. The opposite side guard-boards u are disposed at an angle, so as to project over the opposite chains Q, and are attached at both ends to the short attaching-arms u', which are secured to the outer sides of the side bars m, thereby providing a connection of the guard-boards with the riddle-frame, so as to be adjusted therewith. 95

Arranged transversely of the riddle-frame M, near the upper outer end thereof, is the 100 transverse agitator-shaft V, which carries, near the opposite ends thereof, the agitator-cams v, which are let into the side frame-bars of the riddle and are adapted to slightly tap on the under side of the chains Q, near 105 their upper ends, in order to agitate any trash that may be riding out and carrying with it thrashed grain, thus relieving the grain and causing it to work back onto the bottom inclined chute-board K, arranged at an angle 110 under the endless riddle and discharging into the bottom discharge-conveyer k, which carries the grain off at one side of the machine. The unthrashed material, which is carried over the upper end of the endless riddle L, 115 falls into the return-conveyer k', which carries such material into the return-spout k², which leads back to the feeding end of the thrashing-machine.

The effective separation of the grain falling onto and through the endless riddle is assisted by means of the separate blast-fans W and W', respectively, the former of which fans discharges an air-current into the falling grain as it drops onto the endless riddle, and also causes the current of air to pass through the grain-space H and into the space beyond the upper end of the carrier F. The other fan, W', discharges under the fan W and under and through the riddle L to complete the 125 wind-separations which were not effected by the fan W, and the blast from the fan W' is controlled by a wind-board w, arranged transversely within the casing at one side of the 130

discharge-conveyer *k* and suitably adjustable at the side of the machine-casing, in order to provide for the proper deflection of the air-current that is directed thereby under the 5 riddle *L*.

By reason of the arrangement of the fans *W* and *W'* it will be obvious that such fans fill the whole rear end of the machine with a strong blast of air, and this blast of air 10 comes contracted by reason of the inclination of the bottom inclined chute-board *K* under the riddle *L* and the rear sharply-inclined cant-board *X* extended above the return-conveyer *k'*, so that the blast of air will be sufficiently strong to carry the straw through and beyond the straw-chute *J* to a sufficient distance so as to dispense with any extra rigging for stacking purposes, and it will therefore be 15 obvious that the herein-described machine 20 may be depended upon to stack its own straw, while at the same time sending the dust, chaff and other foreign matter clear away from the machine.

The rear cant-board *X* forms the rear end 25 wall of the machine-casing and leads downwardly to the return-conveyer *k'*, and the said board is at a steeper or sharper inclination than the board *K* and is provided therein with bottom grain-pockets *x* that may be opened 30 from time to time to relieve the machine from extra accumulations of trash. The sharp inclination of the board *X* permits the lighter grains to run down the same against the wind and into the return-screw *k'*, so that such 35 grains are not lost, and if it is found that too much trash is running down the said board *X* into the conveyer *k'* either more wind is given to the machine or the pockets *x* opened to allow the trash to drop out to the ground, where 40 it may be saved for feed or other purposes.

In the grain-space *H*, directly beyond the upper end of the carrier *F*, and the space directly above the upper end of the endless riddle *L* are located the transversely-arranged 45 slowly-rotating grain-wheels *Y*. The said grain-wheels *Y* essentially comprise a shaft *y* and a series of curved wheel-blades *y'* curved in the same direction to form grain-pockets *y*² therebetween. The said grain-wheels 50 rotate in the direction of the arrows and relative to the function of the wheel located in the space *H*. It is to be noted that in practice it has been found that the throw of the slats of the carrier *F*, which carries the grain 55 over the board *E*, and the wind from the fan *W* brought the grain too near the upper end of the riddle *L*, and by the interposition of a grain-wheel of the construction described such wheel will interrupt the grain delivered 60 over the upper end of the carrier *F*, and while the wind passes most of the chaff beyond such wheel the grain falls into the pockets thereof and is dropped and at the same time spread onto the riddle *L* as the said wheel slowly revolves. The grain-wheel located above the 65 upper end of the riddle *L* interrupts and catches the light grains blown over the riddle

and deposits the same onto the board *X*, down which the grain slides into the return-conveyer *k'*.

70

Arranged transversely within the machine-casing *A*, and directly above the winged beater *G*, is the transverse suction-box *Z*, provided at the bottom with a curved screen-bottom *z*, disposed in very close proximity to 75 the periphery of the said wheel *G*, and to each end of the suction-box *Z* is connected a wind-leg *z'*, that also connects with the side inlets of the fan *W'*.

By reason of the arrangement of the suction-box *Z* and its connection with one of the fans of the machine a comparatively dustless machine is provided, for when the machine is in operation the fan *W'* receives its draft through the said suction-box and the wind-leg from the space directly over the beater *G*, so that the "pull" or "draw" comes in from the cylinder, carrying in the dust, &c. The curved bottom screen *z* prevents any straw that might be drawn from the beater 90 from passing to the fan, and the close proximity of such screen to the beater provides means so that the blades of the beater will keep the screen clean and prevent straw and trash from clogging the same to interrupt the 95 blast. The said wind-legs may be provided with suitable means, such as slides, for regulating the draft or blast of the fans with which they are connected.

With reference to the function of the riddle *L*, at this point it is to be noted that the said riddle is adjusted at such an angle that the tendency of the grain to be elevated thereby is overcome by the tendency of the grain to slide toward the lower end thereof, and inasmuch as there is no appreciable jump or jar on the riddle-screens the grain easily 100 passes through the riddle, while at the same time all light trash is moved forward by the riddle and the wind, thereby securing almost 105 perfect separation of the grain.

Changes in the form, proportion and the minor details of construction may be resorted to without departing from the principle or sacrificing any of the advantages of this invention.

Having described the invention, what is claimed, and desired to be secured by Letters Patent, is—

1. In a thrashing-machine, the combination 110 with the casing; of a series of inclined differentially-speeded slatted straw-carriers arranged successively in advance of each other, separate pairs of beaters arranged between and above said carriers and being of a uniform size, said pairs of beaters being differentially speeded progressively and the beaters of each pair being also differentially speeded progressively with respect to each other, the beaters directly above an intermediate point of the carriers being disposed progressively nearer to the upper side of the carrier directly therebelow, and suitable separating devices, substantially as set forth.

115

120

125

130

135

2. In a thrashing-machine, the combination with the casing and the thrashing devices; of an inclined endless grain-riddle pivotally supported at its upper end within the lower part 5 of the casing near one end and essentially comprising a series of flat self-adjusting overlapping screen-plates forming a slide-surface for the grain, means for raising and lowering the unpivoted end of the riddle to adjust the 10 inclination thereof, a stop-board arranged at right angles to and disposed above the lower end of the riddle and carried by the frame of the riddle, whereby the stop-board maintains a fixed relative position irrespective of the 15 inclination of the riddle, and inclined guard-boards located at opposite sides of the riddle and also carried by the frame thereof, said stop and guard boards being adapted to hold the grain on the upper surface of the riddle 20 until it works through the perforations in the screen-plates, substantially as set forth.
3. In a thrashing-machine, the combination with the casing and the thrashing devices therein, of an inclined riddle-frame pivotally-supported at its upper end within the lower part 25 of the casing near one end thereof, means for fastening or securing the riddle-frame at different inclinations, endless chains mounted to travel around the frame and having inter- 30 gral inwardly-extending pivot-pins, transverse plate-bars having perforated flanged ends loosely engaging said pivot-pins, self-adjusting screen-plates fastened at one end to the plate-bars and adapted to slightly overlap 35 the opposite chains and each other, an agitator-shaft arranged transversely within the riddle-frame near the upper end thereof, and agitator-cams mounted on said agitator-shaft at opposite sides of the riddle-frame and 40 adapted to tap against the under sides of the endless chains near their upper ends to loosen the thrashed grain from the trash that is being carried out over the upper end of the riddle, substantially as set forth.
4. In a thrashing-machine, the combination 45 of the casing provided at its rear end with an upper straw-chute, a lower-inclined chute-
- board K and a sharply-inclined cant-board X located between the straw-chute and said chute-board and provided with grain-pockets 50 x, conveyers arranged at the lower ends of said chute and cant boards, the thrashing devices arranged within the casing, a separating-riddle arranged longitudinally over said chute-board, and two fans mounted within the casing and one of which directs a blast longitudinally over the riddle and the other of which directs the blast longitudinally under the riddle and directly over the boards K and X, substantially as set forth. 55
5. In a thrashing-machine, the combination with the casing; of the inclined grain-carrier, a series of straw-carriers arranged above and beyond the grain-carrier and delivering grain into a common grain-space, a separating-riddle 60 arranged within the casing below and beyond the grain-carrier, and slowly revolving grain-wheels mounted within the casing directly above the riddle within said grain-space, and also above the upper end of the 65 riddle, said wheels being adapted to rotate in a direction toward the grain-carrier and comprising a shaft and a series of blades curved in the same direction to form grain-pockets therebetween, substantially as set forth. 70
6. In a thrashing-machine, the combination with the casing; of the straw-carrier arranged in rear of the cylinder of the machine, a revolving beater arranged over said carrier, the separating devices, a fan directing a blast 75 toward said separating devices, a suction-box arranged transversely at the top of the casing and provided with a curved screen bottom lying in close proximity to the periphery of said beater, and wind-legs connecting the opposite ends of said suction-box with the inlets of said fan, substantially as set forth.

In testimony that I claim the foregoing as my own I have hereto affixed my signature in the presence of two witnesses.

WILLIAM J. RANDOLPH.
